UNITED STATES PATENT OFFICE.

ARTHUR R. KRAUSE, OF WOODHAVEN, NEW YORK, ASSIGNOR TO MAX SCHAFER CO., INC., A CORPORATION OF NEW YORK.

DESIGN FOR A LIGHTING-FIXTURE BAR OR ARTICLE OF ANALOGOUS NATURE.

Application filed June 28, 1928. Serial No. 27,301. Term of patent 7 years.

To all whom it may concern:

Be it known that I, ARTHUR R. KRAUSE, a citizen of the United States, and a resident of Woodhaven, county of Queens, and State of New York have invented a new, original, and ornamental Design for a Lighting Fixture Bar or Article of Analogous Nature, of which the following is a specification, reference being had to the accompanying drawing, forming a part thereof.

In the drawing:

Figure 1 is a front elevational view of the lighting fixture bar or article of analogous nature; and Figure 2 is a diagrammatic side elevational view of the same.

I claim:

The ornamental design for a lighting fixture bar or article of analogous nature substantially as shown.

ARTHUR R. KRAUSE.
